CYCLOALKANE OXIDATION

Francis T. Wadsworth, Dickinson, Tex., assignor
to Pan American Refining Corporation, Texas
City, Tex., a corporation of Delaware

No Drawing. Application May 26, 1950,
Serial No. 164,603

6 Claims. (Cl. 260—533)

1

This invention relates to a catalytic process for the oxidation of cycloalkanes to produce principally alkane dicarboxylic acids. More particularly, this invention relates to a catalytic process for the oxidation of cyclohexane with added molecular oxygen in the presence of a reaction medium and solvent consisting essentially of acetone.

In processes for the oxidation of cycloalkanes containing 4 to 6 carbon atoms, inclusive, in the ring by means of oxygen and a polyvalent heavy metal catalyst, the use of a reaction solvent was found to be essential in order to procure commercially significant yields of the desired alkane dicarboxylic acids. This has been found to be particularly true in processes of the above-mentioned type when applied to the oxidation of cyclohexane to produce alkane dicarboxylic acids, particularly adipic acid. When cyclohexane is oxidized in the presence of soluble cobalt and/or manganese carboxylates in the absence of a reaction solvent, even the employment of severe operating conditions leads to the production of cyclohexanol, cyclohexanone, and combustion products such as CO, CO₂ and water, but not to the formation of adipic acid. When cyclohexane is oxidized in solution in butyl acetate in the presence of polyvalent heavy metal carboxylate catalysts, essentially the same oxidation products are obtained as when no solvent whatever is employed; when glacial acetic acid is substituted as the solvent, adipic acid is produced. The solvent plays an important role in catalytic processes for the oxidation of cycloalkanes to alkane dicarboxylic acids, but this role is obscure and cannot be correlated with the solvent capacity of the solvent for the cycloalkane. Up to the present, the only solvent which has achieved practical significance in the type of process here under consideration is glacial acetic acid.

While glacial acetic acid leads to substantial production of adipic acid in processes for the oxidation of cyclohexane with air or oxygen in the presence of soluble polyvalent metal salts, its use is nevertheless attended by certain serious disadvantages. Although acetic acid is not generally considered to be a highly corrosive medium, it actually becomes an extremely corrosive medium under the conditions employed in oxidation processes of the type above described. Aerated acetic acid is a highly corrosive medium even at atmospheric pressure and 115° C., as shown by the following corrosion rates, given as inches penetration per year.

2

	Atmospheric Pressure (115° C.)	
	Liquid Phase	Vapor Phase
304-Stainless Steel	0.082	0.013
309-Stainless Steel	0.080	0.016

Hastelloy-B	0.014	0.005
Hastelloy-C	0.0005	
Al: 3S-H14	0.02	

15 Acetic acid is even more corrosive when employed under moderate oxygen pressures such as are used in processes of the above-described type. Thus, at a temperature of 100-105° C. and 150 p. s. i. g. air pressure, the corrosion rate of 20 Hastelloy-C is increased to 0.0027 I. P. Y. in the liquid phase. At the higher partial pressures of oxygen normally employed in the catalytic oxidation of cycloalkanes, for example, oxygen partial pressures of about 100 to 300 p. s. i. g., acetic acid is even more corrosive. The corrosion characteristics of acetic acid-oxygen mixtures have necessitated the employment of relatively expensive and specially fabricated equipment in processes for the catalytic oxidation of cycloalkanes, for example, equipment lined with tantalum, special stainless steels and the like.

The known processes for the oxidation of cycloalkanes to alkane dicarboxylic acids invariably yield intermediate oxidation products, particularly cycloalkanols and cycloalkanones. 35 When glacial acetic acid is employed as the reaction solvent, cycloalkanols are not recoverable as such from the reaction mixture, but principally as cycloalkanol acetates. The recovery of these esters and their treatment to regenerate the cycloalkanol and acetic acid, respectively, constitute further problems and deficiencies connected with the employment of glacial acetic acid as the reaction solvent in processes of cycloalkane oxidation.

One object of this invention is to provide a novel solvent for use in the oxidation of cycloalkanes to produce principally alkane dicarboxylic acids. Another object of this invention 50 is to provide a novel solvent for use in the oxidation of cyclohexane, cyclopentane, cyclobutane and their methyl- or ethyl-substitution products in the presence of polyvalent heavy metal catalysts to produce alkane dicarboxylic acids. An 55 additional object of this invention is to provide a

process for the oxidation of cyclohexane in solution in a solvent consisting essentially of acetone in the presence of certain heavy metal catalysts to produce substantial yields of adipic acid, together with cyclohexanol and cyclohexanone. Yet another object of my invention is to provide a novel combination of acetone solvent and manganese and cobalt adipates for employment in the oxidation of cyclohexane to produce adipic acid, cyclohexanol and cyclohexanone. These and other objects of my invention will become apparent from the ensuing description thereof.

The process of this invention will be described principally by reference to the oxidation of cyclohexane, although it should be understood that it may likewise be applied to other cycloalkanes containing 4 to 6 carbon atoms, inclusive, in the ring or to their methyl- or ethyl-substitution products. It will also be apparent that the process of the present invention is not limited to the employment of substantially pure cycloalkane charging stocks, but may likewise be applied to natural or synthetic cycloalkane-containing fractions, particularly to such fractions which are derived from petroleum, or from synthesizing operations applied to petroleum fractions, for example, Friedel-Crafts-catalyzed isomerization of methylcyclopentane fractions to cyclohexane.

Briefly, the process of the present invention comprises the oxidation of a solution of cyclohexane in acetone, the latter being present in amounts ranging from about 10 to about 70 weight percent, based on the mixture of acetone and cyclohexane, in the presence of a soluble polyvalent heavy metal oxidation catalyst of the type of manganese, cobalt and copper; oil-soluble salts, for example acetates, naphthenates, oleates, adipates, etc., of the aforementioned and similar heavy metals, or mixtures of oil-soluble salts of manganese, cobalt, copper and the like. The catalyst concentration in the reaction mixture can be varied between about 0.001 and about 0.1 percent by weight (calculated as metal), and is preferably selected between about 0.015 and about 0.033 percent by weight, based upon the weight of the cycloalkane charging stock. The process is effected at temperatures between about 100 and about 140° C., preferably between about 120° C. and about 130° C., employing oxygen partial pressures between about 100 and about 300 p. s. i. g., preferably about 175 to about 225 p. s. i. g. The reaction period may vary between about 1 and about 8 hours, but is preferably selected in about the 2 to 4 hour range.

It is highly surprising to find that acetone could be employed as the reaction solvent in cycloalkane oxidation processes, since acetone is known to be readily oxidizable when treated with oxygen in the presence of polyvalent heavy metal oxidation catalyst in the presence of acetic acid. Acetone oxidizes under these conditions with remarkable ease in the absence of a cycloalkane (note Examples 3 and 4 of U. S. Patent 2,005,183, Walter Flemming et al., patented June 18, 1935) and even when a cycloalkane such as cyclohexane is present, as shown by the following experiment.

A mixture of 768 g. cyclohexane, 156 g. acetone, 159 g. acetic acid, 9.5 g. cyclohexanone (reaction initiator), and 0.2 g., each, of cobalt and manganese acetates was subjected to a temperature of 123-126° C. and a partial pressure of oxygen of 200 p. s. i. g. for a period of 5½ hours. The reaction mixture was then allowed to cool to

room temperature, whereupon unreacted cyclohexane formed a supernatant layer, which was decanted. The lower layer of reaction products was distilled under a pressure of 200 mm. of mercury and the resultant distillate was redistilled at atmospheric pressure, with the results shown in the following tabulation.

The atmospheric boiling point of acetone is 56° C. It will, therefore, be apparent that acetone must have oxidized completely under the conditions employed in the oxidation reaction, since no trace of it was found in the reaction products. The operation yielded 11.1 weight percent of adipic acid, based on the cyclohexane charged, with an ultimate conversion of 36.9 weight percent of the charge to adipic acid.

In marked contrast, as will be shown in detail hereinafter, I have found that when acetone is employed as the sole reaction solvent, in the absence of acetic acid, substantially no acetone oxidation occurs in the presence of a cycloalkane charging stock, but instead selective oxidation of the cycloalkane occurs to produce a commercially desirable yield of alkane dicarboxylic acid, accompanied by cycloalkanone and free cycloalkanol. More particularly, I have discovered that the oxidation of cyclohexane in a solvent consisting essentially of acetone in the presence of certain soluble polyvalent heavy metal salts proceeds smoothly to produce commercially attractive yields of adipic acid, cyclohexanol and cyclohexanone. I have found acetone to be resistant to oxidation under these conditions and readily recoverable from the resultant reaction mixtures. Thus, in the oxidation of cyclohexane in solution in acetone to produce adipic acid, I have found that the total distillate from a typical operation contains acid equivalent only to about 0.65 percent acetic acid. Acetone recoveries of 95-97 percent and even more can be obtained. I have, moreover, discovered that the influence of acetone upon cyclohexane oxidation is specific and that other ketones such as diphenyl ketone do not exert this influence.

In order to afford specific illustrations of the process of the present invention and without the intention of unduly limiting the scope thereof, run data are set forth in the following table. Small proportions of cyclohexanone, as shown, were employed in these runs as a reaction "initiator," i. e. as a material which served to reduce the rather extended induction period before the onset of reaction which would otherwise be experienced. I have found that acetone does not function as an initiator in the catalytic oxidation of cyclohexane.

The inability of acetone to function as a reaction initiator is demonstrated by the following experiment. A mixture of 61 g. of cyclohexane (85% purity), 38.5 g. of acetone and 0.07 g., each, of cobalt, manganese and copper acetates was treated with oxygen at a partial pressure of

200 p. s. i. g. for 3½ hours at temperatures between 126 and 132° C. without evidence of any

the corresponding acetates the induction period varies from about 45 to 90 minutes.

oxygen absorption (drop in pressure) whatsoever. The reaction bomb was then opened and 0.95 g. cyclohexanone was added to the reaction mixture. The reaction bomb was then repressured with oxygen, reheated to reaction temperature and it was found that the pressure began to drop about 20 minutes after the bomb reached reaction temperature. The yield of adipic acid recovered was 8 weight percent, based on the cyclohexane charged. It should be pointed out that the recovery was somewhat inefficient, so that the true yield of adipic acid was somewhat higher.

Referring to the table, the reported adipic acid yields are based solely upon adipic acid filtered from the reaction mixture. It should be borne in mind that additional adipic acid can readily be produced from the initial filtrate.

Run 1 demonstrates the applicability of manganese acetate and run 2 of cobalt acetate as catalysts for the oxidation of cyclohexane in the acetone solvent. In run 3 a mixture of manganese and cobalt acetates was employed. In runs 4 and 5 manganese-cobalt acetate catalysts were employed at reduced acetone concentrations.

Run 6 indicates that copper acetate is a less active catalyst than cobalt and manganese acetates under comparable conditions, but run 7 indicates that copper acetate can be employed together with both manganese and cobalt acetates.

Manganese and cobalt adipate catalysts were employed in runs 8 to 18, inclusive. The adipate salts were prepared by heating a mixture of cobalt and manganese acetates with adipic acid for 3-4 minutes at 130-140° C. The adipic acid employed in preparing the cobalt and manganese adipates was an adipic acid filtrate from a previous oxidation run. The adipic acid filtrate also contains cyclohexanone. The use of manganese and cobalt adipates thus prepared has been found to result in induction periods of the oxidation reaction from 15 to 30 minutes, whereas with

Runs 8 to 10, inclusive, were conducted at a partial oxygen pressure of 150 p. s. i. g., with acetone concentrations varying between 30 and 50 weight percent of the cyclohexane-acetone mixture. The trend discernible from this variation is that the extent of cyclohexane conversion per pass decreases somewhat with increasing cyclohexane dilution, but that a somewhat higher adipic acid yield is obtainable at increased dilutions.

Runs 11 to 14, inclusive, indicate that increasing dilution of the cyclohexane in the reaction mixture can be more or less offset by employing increased oxygen partial pressures (200 p. s. i. g.), whereupon increased adipic acid yields, based on charge, are obtained, but the ultimate yield of adipic acid is somewhat reduced.

Runs 15 to 18, inclusive, illustrate the fact that at relatively high oxygen partial pressure (250 p. s. i. g.), relatively dilute reaction systems can be employed and a high adipic acid yield per pass without undue ultimate adipic acid yield loss can be obtained.

It should be understood that conventional separation techniques can be employed in connection with the process of my invention. One conventional procedure which I have employed following batch operation of the present oxidation process is to distill the reaction mixture to a bottoms temperature of 141° C. to remove acetone, unconverted cyclohexane and water as distillate. The distillation residue is then cooled to -18° C. to crystallize adipic acid, which is thereafter separated by filtration. The adipic acid filtrate can be readily oxidized, for example, with nitric acid, to yield additional adipic acid. A typical adipic acid filtrate was found to analyze as follows.

	Weight per cent of filtrate
Cyclohexanol-cyclohexanone	26
Adipic acid	23
Higher molecular weight acid	51

In runs 8, 9 and 10 the adipic acid filtrates amounted to 17.2, 13.1 and 13.9 weight percent, respectively, based on the cyclohexane charged. Oxidation of these filtrates with 40 percent nitric acid was effected in two steps. The first step was carried out with 40 percent nitric acid at 50-55° C. in the presence of a trace of copper, the nitric acid being reduced in this step to N_2O . In the second step the temperature was raised to 60° C., at which it was maintained for 1 to 1.5 hours while the nitric acid was reduced to NO_2 . The total reaction time in both steps was 2-2.5 hours. It was found that the yields of adipic acid, based on the adipic acid filtrate of runs 8, 9 and 10, were 85.5, 88.0 and 80.0 weight percent, respectively. The overall adipic acid yields in runs 8, 9 and 10 were, thus, 29.7, 26.0 and 20.5 mol percent, based on cyclohexane charged, and 77.8, 81.5 and 86.0 mol percent, based on the cyclohexane converted.

In a study of the use of ketones other than acetone for the oxidation of cyclohexane to adipic acid, an oxidation was carried out in which 30 g. of benzophenone (diphenylketone) were used as the solvent for 62 g. of cyclohexane. Catalysts consisting of cobalt acetate, manganese acetate, copper acetate (.01 g. each) and 1 percent cyclohexanone were used. A reaction period of 4 hours at 125-130° C. and an oxygen pressure of 100-250 p. s. i. g. were used. Only a slight drop in oxygen pressure was noted, with a 3 weight percent yield of adipic acid, based on the cyclohexane charged, being recovered. It is obvious that benzophenone is not equivalent to acetone.

Having thus described my invention, what I claim is:

1. In a process for the liquid-phase oxidation of a liquid cycloalkane containing 4 to 6 carbon atoms, inclusive, in the ring to produce an alkane dicarboxylic acid in the presence of a polyvalent heavy metal catalyst and cyclohexanone reaction initiator, the improvement which comprises effecting said oxidation in a solution of said cycloalkane in a solvent consisting essentially of acetone, the proportion of acetone in said solution being between about 10 and about 70 percent by weight.

2. In a process for the liquid-phase oxidation of cyclohexane to produce adipic acid in the presence of a polyvalent heavy metal catalyst and cyclohexanone reaction initiator, the improvement which comprises effecting said oxidation in a solution of cyclohexane in a solvent consisting essentially of acetone, the proportion of acetone in said solution being between about 10 and about 70 percent by weight.

3. In a process for the liquid-phase oxidation of cyclohexane to produce adipic acid in the presence of a polyvalent heavy metal catalyst selected from the group consisting of carboxylates of cobalt, manganese and cyclohexanone reac-

tion initiator and both cobalt and manganese, the improvement which comprises effecting said oxidation in a solution of cyclohexane in a solvent consisting essentially of acetone, the proportion of acetone in said solution being between about 10 and about 70 percent by weight.

4. In a process for the liquid-phase oxidation of cyclohexane to produce adipic acid in the presence of a polyvalent heavy metal catalyst selected from the group consisting of carboxylates of cobalt, manganese and both cobalt and manganese, at a temperature between about 100° C. and about 140° C., oxygen partial pressure between about 100 and about 300 p. s. i. g. and in the presence of a cyclohexanone initiator, the improvement which comprises effecting said oxidation in a solution of cyclohexane in a solvent consisting essentially of acetone, the proportion of acetone in said solution being between about 10 and about 70 percent by weight.

5. A process for the oxidation of cyclohexane to produce adipic acid, which process comprises subjecting cyclohexane and a solvent consisting essentially of acetone in proportions between about 10 and about 70 percent by weight, based on both cyclohexane and acetone, to treatment with oxygen at a partial pressure between about 150 and about 250 p. s. i. g. at a temperature between about 120° C. and about 135° C. in the presence of an adipate of a polyvalent heavy metal selected from the class consisting of cobalt and cyclohexanone reaction initiator, manganese and both manganese and cobalt, and thereafter separating adipic acid from the reaction mixture.

6. A process for the oxidation of cyclohexane to produce adipic acid, which process comprises subjecting cyclohexane and a solvent consisting essentially of acetone in proportions between about 10 and about 70 percent by weight, based on both cyclohexane and acetone, to treatment with oxygen at a partial pressure between about 150 and about 250 p. s. i. g. at a temperature between about 120° C. and about 135° C. in the presence of an adipate of a polyvalent heavy metal selected from the class consisting of cobalt, manganese and both manganese and cobalt, and initially present cyclohexanone in an amount between about 0.1 and about 1.0 percent by weight, based on cyclohexane, and thereafter separating adipic acid from the reaction mixture.
